[57] CLAIM

The ornamental design for a lamp base, as shown and described.

DESCRIPTION

FIG. 1 is a front elevational view of a lamp base showing my new design, the rear and sides being identical thereto, except for the circular aperture on the bottom edge of the base;

FIG. 2 is a top plan view thereof; and

FIG. 3 is a bottom plan view thereof.

FIG. 3
